SEWING MACHINE ATTACHMENT

Robert Toombs Cozart, Jr., Goldsboro, N. C.

Application December 9, 1947, Serial No. 790,476

7 Claims. (Cl. 112—2)

1

This invention relates to an attachment for sewing machines and more specifically to an attachment to aid in the sewing of elastic tape in waist bands of garments.

The usual procedure in sewing elastic tapes in waist bands is for the operator of a sewing machine to hold the material and the elastic tape together in a stretched condition and sew the tape and the material in relatively short sections. The sewing operation is frequently interrupted as the operator changes her grip on the garment to sew the tape completely around the waist band. The frequent interruptions make it extremely difficult to form a straight seam around the garment. Another disadvantage is that the continual stretching of the material and the elastic tape causes considerable operator fatigue. Moreover it is not possible to maintain the elastic in a uniformly stretched condition when a short section of the waist band is sewed at one time.

Efforts heretofore made to overcome the objections to the operator stretching a series of short sections of the waist band and holding the material in the stretched condition while the elastic tape is sewed to the material have generally required a special sewing machine. Because of the numerous general purpose machines now in use and their long period of satisfactory use, it is desirable to provide an attachment which will aid in the sewing of elastic bands to garments which may be installed on existing general purpose sewing machines.

It is an object of this invention to provide an attachment for a sewing machine and a method of constructing waist bands which will greatly increase the rate at which an operator can form waist bands containing elastic tape on garments.

Another object of this invention is to provide a method and apparatus for forming waist bands which will greatly lessen operator fatigue.

Still another object of this invention is to provide an attachment for running tape in a waist band which may be installed on all general purpose domestic or industrial machines commonly in use.

A further object of this invention is to provide an attachment which will aid in the construction of elastic waist bands in which the elastic tape is under a uniform tension when the waist band is stretched.

Still another object is to provide an attachment which will allow the sewing of straight seams as the elastic tape is secured in the waist band of a garment.

With these and other objects in mind which

2

will become apparent in the detailed description of the invention following, this invention resides in an elongated arm extending substantially parallel to the line of feed of a sewing machine and horns protruding from the ends of the arm substantially perpendicular thereto. The elastic tape and the garment in which the waist band is to be constructed is stretched over the horns which hold the material under a uniform tension in position for feeding to the sewing machine. This invention further contemplates a new method of forming a waist band.

In the drawings:

15 Figure 1 is a perspective view of a sewing machine on which the attachment of this invention has been installed.

Figure 2 is an end perspective view of the sewing machine illustrated in Figure 1.

20 Figure 3 is a detailed perspective view of the feed plate, presser bar and presser foot of the sewing machine on which a guard forming part of this invention has been installed.

Figure 4 is a detailed plan view of the sewing machine attachment illustrated in Figure 1.

25 Figure 5 is a plan view partially in section of a modification of an element of this invention.

Figure 6 is a cross sectional view, along the section line 6—6 in Figure 4, illustrating the resilient construction of the attachment.

Figure 7 is a sectional view along the line 7—7 in Figure 4.

Figure 8 is a vertical sectional view taken along the section line 8—8 in Figure 4.

30 Figure 9 is a vertical sectional view taken along the section line 9—9 in Figure 4.

Figure 10 is a diagrammatic perspective view showing the first step in the method of inserting the tape according to this invention.

35 Figure 11 is also a perspective view somewhat diagrammatic in nature showing a further step in the formation of the waist band.

Figure 12 is a perspective view illustrating the final step in the formation of the waist band according to this invention.

40 Figure 13 is a cross sectional view of the waist band structure at the stage illustrated in Figure 11.

Figure 14 is a cross sectional view of the completed waist band prepared according to this invention.

45 Figure 15 is a plan view of an embodiment of a horn used with the attachment of this invention.

50 This invention will be herein described as em-

ployed in the construction of elastic waist bands on garments. The invention may, of course, be employed for other purposes, and, in general, may be used advantageously wherever it is desired to run an elastic tape along a fabric.

Referring to Figure 1 a sewing machine, indicated generally by 1, is shown mounted on a table 2. The sewing machine 1 is of any conventional type and consists of a base plate 3 inset in the table and on which a housing 4 is mounted. A gooseneck 5 extends from one side of the upper end of housing 4 and joins a head 6 in which is located the mechanism for actuating the needle 7. A fly wheel 8 is provided at the upper end of the housing 4 on the side opposite the gooseneck for imparting a uniform rate of movement to the machine. A presser bar 9 extends from the lower end of head 6 and supports a presser foot 10 which engages the feed mechanism 11 in the work plate 12 of the machine. The above mentioned elements of the machine are conventional parts of the ordinary sewing machines and do not form a part of this invention.

A bracket 13 is secured to the base plate 3 of the machine below the head 6 near the work plate 12. Bracket 13 serves as a mounting for an arm 14 extending substantially parallel to the line of feed of the sewing machine. Horns 15 and 16 extend from the rear and forward ends of the arm 14, respectively, toward the line of feed of the machine for the reception of the garment in which the waist band is to be constructed.

Referring to Figure 4, bracket 13 is shown attached to base plate 3 by a pair of screws 17 and 18. Screws 17 and 18 fit in the holes present in most sewing machines for the reception of a guiding attachment. The base of bracket 13 is slotted at 19 to allow the bracket to be adjusted to a position nearer or farther away from the line of feed of the sewing machine as is required by the width of the waist band. Ears 20 and 21 protrude upwardly from the base of the bracket 13 for the support of the arm 14. The ears clamp arm 14 to hold it rigidly in place and are provided with screws 22 and 23 to allow them to be tightened.

In the preferred form of the attachment illustrated in Figure 4, arm 14 consists of a central sleeve portion 24 which is clamped in bracket 13 and is of tubular construction at the end sections 25 and 26 for the reception of rods 27 and 28, respectively. Rod 27 is drilled and tapped at 29 for the reception of a bolt 30. Bolt 30 passes through a slot 31, similar to the slot 35, in the section 25 of sleeve 24 and locks against the sleeve to hold rod 27 firmly in position. By loosening bolt 30 rod 27 may be slid to the desired position and then locked firmly in place by tightening the bolt. For convenience the section 25 of the sleeve may be calibrated as indicated at 32 to indicate the size of the garment for which the attachment is set.

Ordinarily section 26 and rod 28 will extend considerably farther towards the rear of the sewing machine than section 25 and rod 27 extend towards the front. This construction allows the operator of the machine conveniently to work close to the needle of the machine without interference by the horn 16. It is preferred that the adjustable and calibrated features provided by bolt 30 and calibrations 32 be on the section of the arm extending towards the front of the machine to facilitate adjustment of the attachment.

Rod 28 is drilled and tapped at 33 for the re-

ception of a pin 34 which extends from the surface of the rod through a slot 35 in the sleeve 24. Pin 34 bears against the ends 36 and 37 of the slot 35 to limit the movement of rod 28 relative to the sleeve. A plug 38 is inserted in the section 25 of the sleeve between the end of the rod 28 and the bracket 13. The movement of plug 38 towards the center of the sleeve is prohibited by a pin 39 passing through the sleeve. Between the outer end of plug 38 and the inner end of rod 28 is a compressed helical spring 40 which continually urges rod 28 outward. When the attachment is not in use spring 40 will force rod 28 to the position indicated in Figure 6 in which the pin 34 bears against the outer end 36 of slot 35. When a garment is in place over the horns 15 and 16, spring 40 is slightly compressed, thereby holding the garment in a stretched condition.

Horns 15 and 16 extend from the ends of the rods 27 and 28 toward the line of feed of the sewing machine. The garment to which the waist band is to be attached fits over the horns and is held thereon in a stretched condition. The horns should be long enough to extend beyond the line of the feed of the machine to allow the garment to be supported on the horns and still move in a straight line from the front horn 16, past the needle, to the rear horn 15 as the tape is sewed to the garment. Ordinarily there will be a tendency for the garment to slide off the end of the horns because the upper run of the garment is held outside of the needle 7 of the machine. The horns are, therefore, preferably constructed at a slightly obtuse angle with the arm 14 as shown in Figure 15. The exact angle required to hold the garment on the horns 15 and 16 is a matter of experiment. Horns 15 and 16 are also equipped with shoulders 41 and 42 and knobs 43 to hold the garment in the proper position on the horns.

A modification of the horns 15 and 16 is shown in Figure 5 of the drawings. In this modification the horns are formed by a shaft 44 of reduced diameter on which a washer 45 rotatably fits. A sleeve 46 is rotatably mounted on the shaft 44. A second washer 47 is installed at the outer end of the shaft 44 and the sleeve 46. The end of shaft 44 is drilled and tapped for the reception of a screw 48 which holds washer 47 in place. The modification of the invention illustrated in Figure 5 provides an attachment with freely rotating horns. This structure will facilitate moving the garment as the waist band is being constructed. In certain instances it may be desirable to insert needle bearings between the sleeve 46 and the shaft 44, or in some instances, sleeve 46 may be motor driven.

Referring to Figure 3, a guard 49 is attached to the presser bar 9 by a screw 50. Guard 49 serves as a shield around the needle to prevent it from becoming entangled with the upper run of a loop of the garment as the waist band is attached on the lower run. In many instances it will be desirable to have the shield somewhat bell-shaped to present a concave outer surface urging the upper run of the garment to which the waist band is being attached upward to hold it clear of the lower run.

The operation of the attachment of this invention may best be understood by referring to Figures 10, 11 and 12 in which the apparatus of this invention is schematically illustrated. The arm 14 is adjusted to locate the horns 15 and 16 the proper distance apart to hold a loop of the gar-

ment in a stretched condition. An elastic tape 51 is joined at its ends to form an endless tape. Tape 51 will normally have a length considerably less than the distance around the horns 15 and 16, the exact length depending upon the tightness with which the garment is to fit. Tape 51 is stretched over the horns 15 and 16 as indicated in Figure 10. The edge 52 of the garment 53 in which the waist band is to be installed is slid over the horns until edge 52 extends past the outer edge 54 of the tape 51.

Edge 52 of the garment is folded over the outer edge 54 of the tape 51 along the lower run 55. The upper run 56 of the endless tape and 57 of the garment 53 are folded back towards the ends of the horns and engage the outer surface of guard 49 surrounding the needle 7 of the sewing machine. The machine is started and the edge 52 is stitched at 59 to the lower run of the tape. The operator guides the lower run of the tape with the edge 52 of the garment into the stitching mechanism. In most cases the feeding mechanism of the machine will move the garment over the horns to allow the machine to operate continuously until the tape is stitched to the garment its full length. In any event, the operator has one hand free to help feed the material to the machine. The stitchings 59 hold the material of the garment securely against both faces of the tape.

The garment and the tape are removed from the horns after the stitching at 59 is completed over the full length of the tape. The edge of the garment and the tape are now reversed by folding the garment inwardly over the inner edge 60 of the tape which completely encases it with the material of the garment 53. The garment is now replaced over the horns 15 and 16 and the upper run of the tape and material of the garment are folded back along the outer surface of the guard 49, and a second row of stitches 61 is run adjacent the line of stitches 59. Stitches 61 completely close the waist band with the elastic secured therein in a uniformly stretched condition.

The tape running attachment herein described facilitates the construction of waist bands having an elastic tape under a uniform tension therein. The attachment eliminates the necessity of the operator making the garments holding the elastic tape in a stretched condition as the elastic is stitched to the garment. Since the operator has both hands free to guide the material as it passes the needle of the sewing machine, the workmanship on the garments is improved. Moreover, the reduced fatigue of the operator results in an important increase in the rate at which they can construct the waist bands.

The attachment herein described may be installed on any of the conventional, domestic and industrial sewing machines of the general purpose type wherein the base plate is inset in the table and its upper surface lies substantially flush with the surface of the table. By stitching along the lower run of the loop of material, the necessity of a special machine allowing the lower loop of the garment to pass under the base of the machine is obviated.

A novel method of constructing a waist band having a tape stitched therein has been described which requires a minimum of steps for the formation of the band. The waist band structure herein described completely encloses the tape with the material of the garment to form a highly satisfactory garment. The reduc-

tion in the steps required for the formation of the waist band increases the rate at which an operator is able to produce the bands.

While the preferred modification of this invention has been described in detail, it is to be understood that the concept of the invention is not limited to those details, but falls within the scope of the appended claims.

I claim:

1. A tape running attachment for a sewing machine comprising an arm supported above the base of the machine parallel to the line of feed of the machine, said arm comprising a central sleeve, a first rod and a second rod slidable in said central sleeve and extending from opposite ends thereof, a slot in the central sleeve adjacent the first rod, a bolt screwed into the first rod extending through the slot and engaging the sleeve to lock the first rod in the desired position, a second slot in the central sleeve adjacent the second rod, a pin attached to the second rod extending through the second slot, resilient means within the sleeve urging the second rod outwardly towards the end of the sleeve, said resilient means including a spring compressed between the end of the second rod and a stop within the sleeve, the pin engaging the end of the second slot to limit the movement of the second rod, and a horn extending from each end of the arm beyond the line of feed of the machine.

2. A tape running attachment for a sewing machine comprising a bracket attached to the base of the machine under the head of the machine, an arm supported in the bracket parallel to the line of feed of the machine, said arm comprising a central sleeve, a first rod and a second rod slidable in said central sleeve and extending from opposite ends thereof, a slot in the central sleeve adjacent the first rod, a bolt screwed into the first rod extending through the slot and engaging the sleeve to lock the first rod in the desired position, a second slot in the central sleeve adjacent the second rod, a pin attached to the second rod extending through the second slot, resilient means within the sleeve urging the second rod outwardly towards the end of the sleeve, said resilient means including a spring compressed between the end of the second rod and a stop within the sleeve, the pin engaging the end of the second slot to limit the movement of the second rod, and a horn extending from each end of the arm beyond the line of feed of the machine, and means adjustably attaching the bracket to the base of the machine to allow adjustment of the bracket in a direction perpendicular to the line of feed of the machine.

3. In a sewing machine having a table and a base plate set therein and substantially flush therewith, a tape running attachment comprising an arm parallel to the line of feed of the machine secured above the base of the machine, a horn extending substantially horizontally from each end of the arm beyond the line of feed to receive a stretch of a garment and tape and hold it in an extended position in the line of feed, said horn extending at an obtuse angle from the arm, and a sleeve rotatable on said horn to facilitate movement of the garment and tape on the horn.

4. In a sewing machine of the general purpose type having a table and a base plate set therewith and substantially flush therewith, a tape running attachment comprising an arm secured to the base plate and spaced above the same and extending parallel to the line of feed of the machine, a horn extending respectively from each end of the

arm toward the line of feed and substantially parallel with the base plate, said horns adapted to hold a loop of the material and an endless band of tape in an extended condition thereover in said line of feed, a guard surrounding at least one side of the needle of the machine to engage the upper stretches of said loop of material and band of tape and hold the same out of the path of movement of the needle while the needle is stitching the lower stretches of tape and material together, and said horns forming obtuse angles with the arm and diverging from the arm to counteract the tendency of movement of the lower stretch of the material and tape from the line of feed occasioned by the engagement of the upper stretch with the guard.

5. A sewing machine attachment for sewing an endless tape to a loop of material comprising an elongated member formed of a central sleeve and a rod slidable therein and extending from one end thereof, a horn carried by the central sleeve and extending laterally therefrom, a second horn carried by the rod at the end thereof projecting from the sleeve, said horns lying substantially in the same plane and adapted to be inserted into the loop of material and tape, spring means interposed between said sleeve and rod and yieldingly urging the rod outwardly toward the end of the sleeve to maintain said horns in spaced relation and to hold the loop of material and tape in a stretched condition while sewing the tape to the material, and means for attaching said elongated member to the sewing machine with the central sleeve thereof extending parallel to the line of feed of the machine and said horns intersecting the plane containing the needle of the machine and the line of feed of the machine.

6. A sewing machine attachment for sewing an endless tape to a loop of material comprising an elongated member formed of a central sleeve and a rod slidable therein and extending from one end thereof, a horn carried by the central sleeve and extending laterally therefrom, a second horn carried by the rod at the end thereof projecting from the sleeve, said horns lying substantially in the same plane and adapted to be inserted into the loop of material and tape, spring means interposed between said sleeve and rod and yieldingly urging the rod outwardly toward the end

of the sleeve to maintain said horns in spaced relation and to hold the loop of material and tape in a stretched condition while sewing the tape to the material, and means for attaching said elongated member to the sewing machine with the central sleeve thereof extending parallel to the line of feed of the machine and said horns intersecting the plane containing the needle of the machine and the line of feed of the machine, and a stationary guard spaced about the needle to hold the upper stretch of said loop of material and tape away from the needle as the lower run of tape is stitched to the lower run of the material.

15. 7. A sewing machine attachment for sewing an endless tape to a loop of material comprising an elongated member formed of a central sleeve and a rod slidable therein and extending from one end thereof, an elongated roller rotatably journaled on the central sleeve and extending laterally therefrom, a second elongated roller rotatably journaled on the rod at the end thereof projecting from the sleeve and extending laterally therefrom, the rotational axes of said rollers lying substantially in the same plane, said rollers adapted to be inserted into the loop of material and tape, spring means interposed between said sleeve and rod and yieldingly urging the rod outwardly toward the end of the sleeve to maintain said rollers in spaced relation and to hold the loop of material and tape in a stretched condition while sewing the tape of the material, and means for attaching said elongated member to the sewing machine with the central sleeve thereof extending parallel to the line of feed of the machine and said rollers intersecting the plane containing the needle of the machine and the line of feed of the machine.
